UNITED STATES PATENT OFFICE.

WILLIAM ARTHUR TOOKE, OF MONTREAL, QUEBEC, CANADA.

COLLAR.

1,243,461.

Specification of Letters Patent. Patented Oct. 16, 1917.

Application filed January 2, 1917. Serial No. 140,265.

To all whom it may concern:

Be it known that I, WILLIAM ARTHUR TOOKE, of the city of Montreal, Province of Quebec, Dominion of Canada, a subject of

5 the King of Great Britain, have invented certain new and useful Improvements in Collars; and I do hereby declare that the following is a full, clear, and exact description thereof.

10 My invention relates particularly to soft collars of the type comprising a band and a fold-over top.

Heretofore, collars of this type have been more or less out of favor owing to the fact 15 that the ends of the top would not remain in position lying with their contiguous edges snugly against the tie. This was due to the fact that the connection between the ends was by means of fastening devices attached 20 to or engaging the outer ply of the collar, it being understood that all collars of this type are two or more ply. The object of my invention is to overcome this defect and provide a collar of this type, the ends of the 25 top of which will not only lie snugly against the tie but will have no visible connection, the fastening device, according to my invention, being attached solely to the under ply. The under ply is free relatively to the 30 outer ply of the fold-over top except at its edges where it is stitched.

More specifically stated the invention consists of a length of flexible material, preferably elastic, connected at its opposite ends to 35 the lining of the respective ends of the top and the connection at both ends being detachable.

For full comprehension, however, of my invention reference must be had to the accompanying drawings in which similar reference characters indicate the same parts, and wherein:

40 Figure 1 is a perspective view of a soft collar provided with my improved fastening;

45 Fig. 2 is a view of the underside of the collar with the front portion spread open to disclose the lining of the top;

Fig. 3 is a fragmentary sectional view taken on line 3—3 Fig. 1; and

Fig. 4 is a detail view of the fastening device removed.

I prefer to make my collars with the top or outer ply *b* of the fold-over top of linen, cotton, silk or other suitable fabric and the under ply *c* of cotton. The connection between the ends of the top is made between the ends of the under ply thereof, and the preferred embodiment consists of a short length *d* of narrow textile elastic fabric one 60 end of which has a button *e* and the other end a hook *f* both being preferably attached by stitching. The under ply of the ends of the fold-over top has button-holes *g* and *h*, while the outer ply is uncut and presents a 65 preferably smooth unbroken surface.

In order to fit a collar having my invention applied thereto and put on a neck-tie correctly, the collar is first buttoned to the shirt-band as usual, the tie being located in 70 the fold of the collar. One end of the fold-over top is then turned up and the button on the fastening device is inserted in the button-hole, the tie being lifted, and the hook at the other end of the attachment length is 75 inserted into the button-hole of the lining of the other end which may be turned back for the purpose. If desired the fastening device may be first buttoned to one end of the top.

Although I have illustrated my invention applied to a collar having sharp points, it may also be applied to a collar having rounded points or any other shape, without departing from the spirit of my invention.

80 What I claim is as follows:—

A soft collar comprising a band and a fold-over top the latter consisting of a plurality of plies free from each other except at their edges, of means detachably connecting the adjacent ends of the fold-over top together, said means consisting of a removable strap of elastic material having a button on one end thereof and a hook on the opposite end and button-holes in the under-ply of the fold-over top for engagement by

the button and hook respectively, the said underply substantially conforming to the outerply for the purpose of causing the tension exerted by the strap to be distributed throughout the said underply of the top, said strap being constructed and arranged to be concealed from view when the collar is in position on the neck of the wearer.

In testimony whereof I have signed my name to this specification in the presence of 10 two witnesses.

WILLIAM ARTHUR TOOKE.

Witnesses:

WILLIAM J. C. HEWETSON,
C. J. E. CHARBONNEAU.
